R. H. ROBINSON

TENNIS RACKET

Filed Aug. 28, 1922

Inventor:
Roy H. Robinson,

By Fisher, Towle, Clapp & Soans
Atts.

UNITED STATES PATENT OFFICE.

ROY H. ROBINSON, OF CHICAGO, ILLINOIS.

TENNIS RACKET.

Application filed August 28, 1922. Serial No. 584,619.

To all whom it may concern:

Be it known that I, ROY H. ROBINSON, a citizen of the United States, residing in Chicago, in the county of Cook and State 5 of Illinois, have invented certain new and useful Improvements in Tennis Rackets, of which the following is a specification.

This invention relates to rackets for lawn tennis, but more particularly to such as are 10 provided with a metal frame, and has for its primary object to produce a frame construction of this type which will not cut the strings of the racket.

Further objects are to provide an improved method of stringing the racket, to 15 permit adjustment of the stringing in the racket, and in general to provide an improved racket.

Metal tennis racket frames are preferable 20 to the present wooden type because of their greater strength and reduced air resistance. The only serious disadvantage of this type of frame has been the frequent cutting of the strings. Wire strings have been tried 25 as a substitute for the usual gut but these have less resiliency and are also cut by the metal edges, although less quickly than the gut.

In order to obviate the disadvantages 30 and retain the advantages of the metal frame racket, I have provided the frame with a cushioning element which prevents the strings from coming in contact with the metal. Also I have provided a new method 35 of stringing which eliminates the sharp bearing angles for the strings on the frame. My improved stringing likewise distributes the blows on different strings throughout the longitudinal zone of impact which in 40 the present type of rackets fall principally on the central longitudinal strings. The adjustability of the frame permits the stringing to be tightened or slackened at will and is particularly advantageous be- 45 cause it relieves the strain upon the stringing when the racket is not in use and permits the tension to be varied in accordance with weather and other conditions.

The many other objects and advantages 50 of my invention will be better understood by reference to the following specification when considered in connection with the accompanying drawing illustrating certain selected embodiments thereof, in which:

55 Fig. 1 is a front elevation of the racket.

Fig. 2 is an enlarged central longitudinal section of a portion of the racket frame.

Fig. 3 is a transverse section on the line 3—3 of Fig. 2.

Fig. 4 is a fragmentary side elevation of 60 the partially formed tubing illustrating the method of slitting the same.

Fig. 5 is a central longitudinal section of a modified form of racket framing.

Fig. 6 is a transverse section on the line 65 6—6 of Fig. 5.

Fig. 7 illustrates a modified form of stringing.

Referring to the drawing and particu- 70 larly to Figs. 1 to 4, the racket comprises a frame 10 provided with the usual handle 11 and stringing 9. The frame 10 varies somewhat in form in various models of racket but is substantially oval in shape and is provided with a shank 12 upon which 75 the handle is secured. The particular design of racket frame illustrated in Fig. 1 of the drawing is similar to that of a well-known make in which the frame is tubular in form. The shank 12 is formed of a pair 80 of tubes 13 which have their outer ends welded to the frame 10. The handle 11 is of wooden construction and is driven upon the tubes 13. A metal ferrule 14 en- 85 velops and supports the forward end of the handle 11. In my improved construction the metal frame 10 is indented in its outer face to form a longitudinally extending channel 15 within which fits a cushioning strip 16 of leather, fiber, or other suitable 90 material. The outer side of the metal tubing, which alone carries the stringing 9, is initially slotted at 17 in the manner indicated in Fig. 4 and the prongs 17' rounded 95 downwardly to provide a smooth bearing surface, having no sharp edges or angular turns to cut the gut strings. The inside wall 7 of the tubular framing is longitudinally slotted at intervals as at 8 to permit the strings to pass inwardly and outwardly 100 without contacting therewith. The cushion 16 is slotted in substantially the same manner as the upper or outer wall of the tube and maintains the strings out of contact therewith, as indicated in Fig. 2. If wire 105 stringing is used the cushioning element might be omitted as the rounded bearing surfaces would not cut this material.

Instead of stringing the racket in the usual manner with the strings extending 110

longitudinally and transversely of the frame, I have provided a new form of stringing in which the strings run obliquely of the frame. This form of stringing has many advantages which make it preferable for either wood or metal frame rackets, but in the case of metal frame rackets it is particularly desirable because each string as it passes through the frame is merely turned through an angle of about 45 degrees instead of making a complete turn or reversal of direction. It has been found in practice that practically all the impacts of the ball occur in a central strip extending longitudinally of the racket so that in the present type of racket a few of the longitudinal strings receive practically all of the impacts and it is these strings which usually break first. In my improved form of oblique stringing these impacts are distributed over practically all the strings. Furthermore, the strings receiving the majority of impacts are shorter in length than in the present type of bracket. In the majority of strokes the racket is caused to strike the ball a glancing blow which usually occurs approximately along the lateral axis of the racket or at a right angle to the longitudinal strings and parallel to the lateral strings in the form of stringing hitherto employed. The object of this is to produce a spin upon the ball. The amount of spin depends upon the friction created by the contact of the ball with the strings of the racket. It has been found that my improved form of stringing very materially increases the frictional resistance and thus proportionally increases the spin. Another advantage of my oblique stringing is that it permits the tightening or loosening of the strings by the adjusting of the size of the frame which would not be possible in the present form of stringing.

In order to make possible the adjustment of the racket frame to either tighten or loosen the stringing, I have provided in the frame small turn-buckles 18 consisting of an interiorly threaded sleeve 19 fitting upon oppositely threaded screws 20 set in the opposing ends of the frame. The sleeve 19 is preferably of substantially the same exterior size as the metal tubing of the bracket. The sleeve 20 is provided with a series of perforations to permit it to be turned by a small pin or key. When these turn-buckles are located at the top and bottom of the frame, as indicated in Fig. 1, each side of the racket forms an arch, and when this is pushed outwardly by the screws the strings are not only tightened but the tightening of the nearest strings forces out the arch in the center until an equilibrium in the tightening of all of the strings is reached. If only one turn-buckle is to be used it is advisable that this be located at the bottom or handle end

of the frame so that the frame may be contracted or spread at this point. The spreading of the lower arch of the racket tightens both sets of strings at their lower end and accordingly the entire stringing of the racket. Any other well-known method of adjusting the size of the frame may be used in place of the turn-buckle described. Instead of placing the adjusting elements at the top and bottom of the frame, or at either of these locations, the adjusting elements may be placed on opposite sides of the racket and this form is advantageous where more longitudinally oblique string is used. The oblique stringing and the adjustment of the frame are equally applicable to both metal and wooden frame rackets, as will be readily evident.

Instead of using a tubular metal frame, such as has been described in connection with Figs. 1 to 4 inclusive, a braced trough-shaped frame 30, such as is shown in Figs. 5 and 6, may be used. In this frame the side members 31 join in a comparatively sharp edge 32 and the outer edges of these sides are preferably rolled over at 33. Metal ties 34 connect these outer edges at suitable intervals and properly brace the frame. A filler 35 of fiber, wood, leather, or other suitable material, is placed within the trough and is held in place therein by the outer rolled edges thereof. This filler is punched or cut away, as at 36, to permit the passage of the strings therethrough and forms the cushion for these strings in the same manner as the strip 16 in the previous embodiment. This form of frame is not only neat in appearance but its concave faces coming to a substantially sharp edge between the stringing conform well to the ball and practically eliminate what is known as "wood shots". The playing area of the racket is extended practically to the outer edge of the frame.

Instead of the form of single stringing illustrated in Fig. 1, the strings may be grouped in pairs with a slight interval between the springs in each pair, in the manner indicated at 40 in Fig. 7. This form of stringing is advantageous, as it provides larger openings 41 for the ball to sink into without reducing the number of strings.

With my improved form of racket it is possible to use gut stringing and the strings will not be cut by the metal of the frame. The oblique form of stringing increases the playing efficiency of the racket and the wearing qualities of the same. It also makes possible the adjustment of the frame with the benefits set forth.

I am aware that many changes may be made in the construction and arrangement of parts without departing from the spirit of my invention, and I reserve the right to make all such as fairly fall within the scope of the following claims.

I claim as my invention:

1. A tennis racket comprising a substantially oval shaped tubular metal frame having a channel formed in its periphery and extending longitudinally thereof, a strip of yielding material fitting within said channel, stringing woven through said frame and said strip, and a handle connected to said frame.
- 5 2. A tennis racket comprising a tubular frame having its outer wall slitted at intervals and the metal pressed inwardly to form a series of string-bearing surfaces, a handle connected to said frame, and stringing passing through the inner wall of said frame and about the bearing surfaces on said outer wall.
- 10 3. A tennis racket comprising a tubular frame having a series of longitudinally spaced slots formed in its inner wall and its outer wall slitted at longitudinal intervals with the metal turned inwardly to form a series of rounded string-bearing surfaces, a handle connected to said frame, and stringing passing through the slots in the inner wall of said frame and about the corresponding string-bearing surfaces on the outer wall thereof.
- 15 4. A tennis racket comprising a substantially oval shaped frame divided transversely on the longitudinal axis thereof, an adjusting element disposed between the opposing ends of said frame, a handle connected to said frame, and stringing woven through said frame.
- 20 5. A tennis racket comprising a substantially oval shaped frame divided transversely on the longitudinal axis thereof, a turn-buckle connecting the opposing ends of said frame, a handle connected to said frame, and stringing woven through said frame.
- 25 6. A tennis racket comprising a substantially oval-shaped frame having a channel therein and extending longitudinally thereof, a strip of yielding material fitting within said channel and retained therein by the conformation of the walls of the channel, stringing woven through said frame and said strip, and a handle connected to said frame.
- 30 7. A tennis racket comprising a metal frame having a series of substantially H-shaped slits provided therein and the prongs formed by said slits pressed inwardly, a handle connected to said frame, and stringing passing through the openings formed by said slits.
- 35 8. A tennis racket comprising a tubular metal frame having a series of slots formed in its inner wall and its outer wall provided with corresponding substantially H-shaped slits, said outer wall being indented to provide a longitudinal channel therein and having the prongs formed by said slits bent inwardly, a strip of yielding material extending longitudinally of said frame within said channel and slitted to correspond with the wall thereof, stringing woven through said frame and said strip, and a handle connected to said frame.
- 40 9. A tennis racket comprising a substantially oval-shaped frame divided transversely at opposite points, adjusting elements located at each of the points of division, a handle connected to said frame and stringing woven through said frame.
- 45 10. A tennis racket comprising a substantially oval-shaped frame, stringing woven through said frame with one set of strings disposed at an angle to the other set, an adjusting element incorporated in said frame between said sets of strings, the strings of each set engaging the frame on opposite sides of said element and a handle connected to said frame.
- 50 11. A tennis racket comprising a frame having an open throat, an adjustable member forming the sole connection between the sides of the frame at the throat, a handle connected to the ends of the frame, and stringing woven through said frame.
- 55 12. A tennis racket comprising a substantially oval-shaped frame, obliquely arranged stringing woven in said frame, means disposed between the sets of stringing for adjusting said frame to vary the tension of said stringing, the strings of each set engaging the frame on opposite sides of said means and a handle connected to said frame.
- 60 13. A tennis racket comprising a substantially oval-shaped metal frame having perforations therein to admit the stringing, stringing woven through said perforations, cushioning means interposed between said stringing and said frame and retaining said stringing out of contact with said frame, and a handle connected to said frame.

ROY H. ROBINSON.
